UNITED STATES PATENT OFFICE.

JOHN R. BEYNON, OF WATERTOWN, WISCONSIN, ASSIGNOR OF ONE-HALF
TO JAMES B. MURPHY, OF SAME PLACE.

ALARM FOR GRAIN-ELEVATORS, &c.

SPECIFICATION forming part of Letters Patent No. 394,815, dated December 18, 1888.

Application filed July 16, 1888. Serial No. 280,054. (No model.)

To all whom it may concern:

Be it known that I, JOHN R. BEYNON, of Watertown, in the county of Jefferson, and in the State of Wisconsin, have invented certain new and useful Improvements in Alarms for Grain-Elevators, &c.; and I do hereby declare that the following is a full, clear, and exact description thereof.

My invention relates to alarms for indicating the choking of elevators, conveyers, spouts, &c., employed in the handling of grain and other loose material; and it consists in certain peculiarities of construction and combination of parts, to be hereinafter described with reference to the accompanying drawings and subsequently claimed.

In the drawings, Figure 1 represents a vertical transverse section of my invention, taken on line 11 of Fig. 2; Fig. 2, a rear elevation of the same, certain of the parts being broken away for the purpose of better illustration; and Fig. 3, a side elevation of the device shown in Fig. 2.

Referring by letter to the drawings, A represents the stock, B the belt, and C the buckets, that form a grain-elevator of ordinary construction. At any convenient place along its length the stock A has an opening in one of its sides, and in this opening is fitted an outwardly-extending casing, D, the latter being preferably arc-shaped at its upper end and provided with a flange, b, by which it is secured to said stock.

An outwardly-inclined deflector-plate, E, depends for a certain distance from the inner edge of the top of casing D and extends from side to side of the latter. Pivoted to the sides of the casing adjacent to the lower edge of the deflector-plate E is a valve, F, that is held in its normal or closed position against the upper end of a discharge-chute, G, by means of an angular extension or counterpoise, H, the latter being of such length that its outer end is always in contact with the arc-shaped top of said casing.

The upper portion of the chute G is turned down to form a deflector-plate, I, that has an inclination opposite to that of the one E, and depending from the under side of said chute is an arc-shaped flange, c, under which works

the angular extension or counterpoise J of a valve, K, the latter being held in its normal or closed position against another chute, L, that leads back into the stock A of the elevator. The chutes G L, being opposite to each other, are so arranged that a space, M, is left between the lower end of the former and the upper end of the latter for the purpose to be hereinafter described.

Pivoted to the sides of the casing D, so as to close against the upper end of the chute L, is a valve, N, the latter being also provided with an angular extension or counterpoise, O, by which it is held in its normal or closed position.

To one end of the pivot d of the valve N is secured an arm, P, that is provided with a right-angular extension, e, arranged to come under another arm, Q, the latter being pivoted to the adjacent outer side of the casing D, as best illustrated in Fig. 3. As illustrated by the drawings, the arm Q has a rod-connection, f, with the pallets g of an ordinary clock-alarm, the latter, for the sake of convenience, being shown attached to the casing D; but it is obvious that this alarm may be located at any point more or less remote from the elevator.

While I have shown and described a clock-alarm in connection with the valve N, it is obvious that I may employ an electric or other suitable alarm without departing from the spirit of my invention.

In the operation of my invention such material as overflows from the buckets C of the elevator will fall against the deflector-plate E, to be guided by the latter down against the valve F, and when the pressure of the material overcomes the resistance of the angular extension or counterpoise of said valve the latter will open and allow said material to escape down the chute G to come against the valve N. If there is enough pressure of the material to overcome the angular extension or counterpoise O of the valve N, the latter will open, and not only allow said material to escape, and thus relieve the elevator in case there is sufficient flow to keep both valves F N open, but at the same time will raise the arm P to in turn actuate the arm Q, and

thereby start the alarm, thus giving notice that the elevator is either choked or about to become so. In case only a small quantity of the material escapes down the chute G, it will 5 drop through the space M onto the chute L and accumulate against the valve K until there is enough to cause said valve to open and let said material back in the elevator-stock to be caught by one of the buckets and 10 carried on to the point of discharge. As there is always more or less air being forced up in the elevator-stock by the movement of the buckets C, the valve K is principally designed as a cut-off, to prevent the air-currents from 15 keeping back the material that may tend to fall through the space M, and also to prevent any opening of the valve N by means of said air-currents; hence it will be seen that by means of the space M and valve K the danger 20 of starting a false alarm is obviated. Either one of the valves F N may be omitted, if found desirable; but the one retained will be necessarily connected with the alarm.

By the employment of the device above described in connection with a grain-elevator 25 the loose material cannot choke up in the stock and stop the belt, and consequently the liability of the latter to be burned by the friction of the drums (not shown) is obviated.

30 While I have shown and described the valves and an alarm mechanism in connection with an elevator, said valves and alarm mechanism can be as readily applied to conveyers, spouts, &c., and I do not therefore wish to be understood as limiting myself to any particular device that may be employed in connection with my improvements for the purpose 35 of handling grain or other loose material.

Having thus fully described my invention, 40 what I claim as new, and desire to secure by Letters Patent, is—

1. The combination, with a grain-elevator or analogous device having one of its sides provided with an opening, of a valve arranged 45 to normally close said opening and an alarm mechanism connected to the valve to signal

the opening of the latter, substantially as set forth.

2. The combination, with an elevator or analogous device for handling grain or other 50 loose material, of a discharge-chute, a valve normally closed against the upper end of the chute and arranged to be actuated by an accumulation of the material, another valve also normally closed against said chute at or 55 near the mouth of the same, and an alarm mechanism connected to the latter valve to signal the opening thereof, substantially as set forth.

3. The combination, with an elevator or analogous device for handling grain or other 60 loose material, of a discharge-chute, a return-chute arranged adjacent to the discharge-chute and communicating therewith, a valve normally closed against said discharge-chute 65 and arranged to be actuated by an accumulation of the material, a cut-off valve normally closed against the return-chute, another valve also normally closed against said discharge-chute, and an alarm mechanism connected to 70 the latter valve to signal the opening thereof, substantially as set forth.

4. The combination, with an elevator or analogous device for handling grain or other 75 loose material, of the casing D, provided with the deflector-plates E I and communicating chutes G L, the valves F N K, pivoted to the sides of the casing and individually provided with an angular extension or counterpoise, the arm P, secured to the pivot of valve N, 80 the pivoted arm Q, arranged to be actuated by arm P, and an alarm mechanism connected to said arm Q, substantially as set forth.

In testimony that I claim the foregoing I have hereunto set my hand, at Watertown, in 85 the county of Jefferson and State of Wisconsin, in the presence of two witnesses.

JOHN R. BEYNON.
